(57) **CLAIM**

The ornamental design for a four compartment condiment holder, as shown and described.

DESCRIPTION

FIG. 1 is a perspective view of a four compartment condiment holder embodying the novel design;

FIG. 2 is a side elevational view thereof, the opposite side being of identical configuration;

FIG. 3 is an end elevational view thereof;

FIG. 4 is a top plan view thereof; and,

FIG. 5 is a bottom plan view thereof.
